MAGNETIC CORE FOR HIGH FREQUENCY
INDUCTANCESWladimir J. Polydoroff, Chicago, Ill., assignor to
Johnson Laboratories, Inc., Chicago, Ill., a cor-
poration of IllinoisApplication December 10, 1934, Serial No. 756,790
In Great Britain December 19, 1933

3 Claims. (Cl. 171—119)

This invention relates to magnetic cores, and more particularly to magnetic cores suitable for use in high frequency inductances. Magnetic cores of this type may be employed, for example, 5 in inductances intended for use in broadcast receivers. The magnetic cores of the present invention are composed of a finely divided magnetic material, the particles of which are insulated from one another and held together by means of 10 a suitable binder.

The invention will be better understood by reference to the accompanying drawing taken in connection with the description to follow.

Figure 1 shows a core and yoke employed in 15 conjunction with a coil which is tuned by external means;

Figures 2 and 2a show a core with a yoke especially adapted for use with an oscillator coil where a constant output frequency is desired.

20 In my United States Patents No. 1,940,228, issued December 19, 1933, and No. 1,982,689, issued December 4, 1934, and in my co-pending United States application No. 535,606, filed May 7, 1931, there are described magnetic cores of the type 25 hereinbefore referred to.

My present invention results from the discovery that the iron losses occurring in an iron core inductance at high frequencies are chiefly due to the minute induced currents generated in particles in close proximity to the coil, and particularly those which lie inside the coil. Likewise the apparent permeability is mostly due to the iron embraced by the coil. It is therefore important to use very finely divided iron of high 35 magnetic properties in the central plug of such a core. The magnetic structure employed to provide a return path for the flux, on the other hand, is subjected to a much lower influence tending to create induced currents and is therefore less important from the standpoint of losses. Thus for 40 instance the outer yoke can be made of coarser and inferior magnetic material without having a serious adverse effect upon the performance of the inductance device as a whole.

45 The present invention may be advantageously employed in inductances having fixed cores, such as for instance, inductances tuned by external means. For example, a magnetic core for a high-frequency inductance may have associated with 50 it a U-shaped yoke to reduce the reluctance of the magnetic flux path and thus to increase the apparent permeability of the core. The yoke in this case also may be made of magnetic material coarser than and inferior to that employed in 55 the core, or in particular cases it may even con-

sist of laminations of sheet magnetic material, thereby greatly reducing the reluctance of the return path. By locating the yoke sufficiently far from the direct influence of the coil, the core losses may be kept sufficiently low despite the 5 lower grade of material employed in the yoke.

In Figure 1, a compressed comminuted magnetic core 6 supports coils 7, which may be of pancake form as shown, and which are connected in series in order to exhibit low loss characteristics. The magnetic yoke 8, may also be of compressed comminuted magnetic material of an inferior grade to that employed in the core 6.

The construction shown in Figures 2 and 2a is of particular value for use in conjunction with the 15 oscillator coil of a superheterodyne receiver. It is well known that such oscillators are subject to frequency drift due to changes in temperature and in the voltage supplied to the oscillator valve. One method for limiting frequency drift due to 20 temperature changes consists in employing a coil provided with a core made of a material having properties such that its apparent permeability also changes with temperature; a material having such properties is, for instance described in my 25 United States Patent No. 1,982,689. Such a core, for example, may be employed in the construction shown in Fig. 1.

It was found that comminuted materials such as disclosed in my United States Patent No. 1,982,689, 30 retain their permeabilities constant through a considerable range of magnetic intensities and are in practice operated far below their saturation points.

According to the present invention it was found 35 useful to employ in certain cases magnetic material whose magnetic properties could be varied, and to provide magnetizing windings by means of which their magnetic properties can be controlled. In the particular case of an oscillator-generator 40 where the losses are of no great importance the return path of the inductance coil (Figure 2) may be of thinly laminated iron employing for instance, silicon iron strips, whereas the core piece 6 surrounded by the windings 7 is made of usual 45 comminuted material. The yoke 8 of this structure is such that its effect on the core piece 8 may be varied by external fields represented by a coil 12 which may be supplied with direct current from either the power supply or the anode circuit of the 50 oscillator valve, or both.

Thus the degree of D. C. magnetization and hence the effective permeability of the core structure and the total inductance of the coil may be made to vary automatically with changes in the 55

power supply or anode voltages. This arrangement effectively limits frequency drifts and maintains the oscillator circuit substantially constant with frequency notwithstanding small variations 5 in the power supply voltage.

Figure 2 shows an elevation of an inductance device arranged for compensation of frequency drifts by D. C. magnetization effect. Figure 2a is a plan view of the same device. A cylindrical 10 magnetic core 6 supports pancake inductance coils 7. The yoke 8 is made of thin laminations of magnetic material, and carries a direct-current winding 12.

It will be understood that the core 6 of this 15 embodiment may be so chosen that its permeability varies in response to temperature variations in a suitable manner as hereinbefore described so that both voltage supply and temperature variations may be compensated for in one 20 instrument.

Having thus described my invention, what I claim is:

1. A frequency-controlling device for use with a generator of high-frequency currents, said generator being subject to frequency fluctuations with changes in operating conditions, including an inductor having a compressed comminuted ferro-magnetic core and a low-loss coil for said high-frequency currents, and means for regulating the 25 inductance of said inductor including a magnetic structure which completes the magnetic circuit of said inductor, said structure being made of material whose magnetic reluctance is varied in response to changes in operating conditions, in such 30 manner as to maintain the frequency of the current delivered by said generator substantially constant.

2. A frequency-controlling device for use with a generator of high-frequency currents energized

from an external power source that is subject to voltage variations which tend to produce fluctuations in the frequency of the current delivered by said generator, including an inductor having a compressed comminuted ferro-magnetic core and a low-loss coil for said high-frequency current, and means for regulating the inductance of said inductor including a magnetic structure which completes the magnetic circuit of said inductor, said structure being made of laminated material 10 whose reluctance may be varied in response to changes in magnetizing current, and a winding for said magnetizing current so connected to said external source of power as to maintain the frequency of the current delivered by said generator 15 substantially constant.

3. A frequency-controlling device for use with a generator of high-frequency currents energized from an external source of power that is subject to voltage variations which tend to produce fluctuations in the frequency of the current delivered by said generator, said generator being also subject to frequency fluctuations with changes in temperature, comprising an inductor having a compressed comminuted ferro-magnetic core 25 made of material whose magnetic reluctance varies in response to temperature, a magnetic structure which completes the magnetic circuit of said inductor made of laminated material whose reluctance may be varied in response to changes 30 in magnetizing current, and a winding for said magnetizing current connected to said external source, whereby voltage variations and temperature changes produce compensating variations in the reluctance of the magnetic circuit so as to 35 maintain the frequency of the current delivered by said generator substantially constant.

WLADIMIR J. POLYDOROFF.
